MACHINE FOR POLISHING, SANDING, AND
THE LIKE

William O. Arnold, Sheboygan, Wis.

Application July 18, 1935, Serial No. 31,983

10 Claims. (Cl. 51—170)

This invention relates to improvements in machines for polishing, sanding and the like.

Among the principal objects which the present invention has in view are: To provide an improved machine as characterized, having means whereby the machine can be used for a plurality of purposes; to provide means for operating the same at a minimum cost; to be enabled to adjust workable parts of the machine without too much delay; to be enabled to use the machine as a sander and/or a rubber; to provide means when used as a sander whereby sandpaper or the like can be readily attached and/or removed in minimum time; to be enabled to employ a double reciprocating means for operating the machine; to grip the sandpaper or the like at the ends thereof which are transverse to direction of movement; to hold the sandpaper or the like under tension and take up slack therein while in use; to obtain straight-line reciprocation of the rubbing and/or sanding element; to reduce to substantial elimination the undesired vibration of the machine; to lubricate the moving parts in use by an application of the lubricant at one place; to spread the exhaust air or other fluid actuating medium; to reduce to a minimum the working parts and to otherwise simplify the construction and use of my improved machine; and to obtain other advantages and results as may be brought out in the following description.

Drawings:

Figure 1 is a view in elevation, looking at what may, for convenience, be termed the front of my improved machine;

Figure 2 is a vertical sectional view, looking in the same direction as Figure 1, and shown as taken on line 2—2 of Figure 3;

Figure 3 is an end elevation;

Figures 4 and 5 are transverse vertical sectional views taken on lines 4—4 of Figure 2 and 5—5 of Figure 1, respectively;

Figure 6 is a plan of the synchronizing connection for the reciprocating platens; and

Figure 7 is a view similar to Figure 2 and showing the adaptability of a sanding tool thereon.

Description:

As seen in the drawings, the reference numeral 10 indicates the machine housing or body having therein a pair of opposed cylinders 11, 11, and 50 which may, for convenience, comprise a single boring so that said cylinders are in direct communication with each other at their inner ends. In each cylinder 11 is a piston 12, and the two pistons are opposed with respect to each other, 55 each with a piston rod 13, shown integral there-

with, projecting from the outer end of the cylinder in which such piston operates.

At the outer end of each piston rod 13 is mounted a coupling 14 the lower part of which interlocks with and supports a slide 15, these parts 5 being shown secured rigidly together by bolts 16. The slide 15 extends partway beneath the body or housing 10, parallel to the axis of the piston 12 and piston rod 13. The inter-engaging surfaces between said slide and the housing are preferably provided with serrations 15' longitudinally disposed in direction of sliding so as to prevent any lateral vibration and to provide a good support and sliding contact. The same serrations in the slide may extend to the outer end thereof if 15 desired and, with similar serrations in the bottom of coupling 14, provide an aligning, non-twisting connection between the slide 15 and coupling 14.

Fluid pressure, such as air, is shown introduced 20 through a suitable coupling A at the top of the housing communicating with a horizontal channel 17 in the housing so as to enter through ports 18 next to the outer ends of the cylinders 11, 11 between the outer face of the pistons 12 and appropriate packing 19. There will consequently always be sufficient pressure on the outer ends of the pistons to actuate the pistons inwardly when there is no applied pressure at the opposite side of pistons. In the piston rods 30 13, I provide one or more radial valve ports 20, which, for most of the stroke, are covered by the packing 19, but which, at the inner stroke position of the pistons will be exposed within the cylinders 11 to receive the pressure communicated thereto through channel 17 and ports 18, 18. The pistons likewise have longitudinal passages 21 therein in constant communication with radial valve ports 20 and opening through the inner ends of the piston. By this course pressure will be 40 introduced to the inner ends of the cylinders and by virtue of that pressure acting upon the entire inner ends of the pistons, the pistons are thereupon both forced outwardly to a position where the inner ends thereof uncover exhaust ports 22 45 opening downwardly toward the slides 15. By this means, an automatically reversing reciprocating motion is imparted to the pistons, piston rods, couplings and slides.

In order to synchronize the movement of the 50 two slides 15 under working conditions, each is preferably provided with a rack 23 extending in a direction longitudinally of the direction of sliding motion of the slides. The racks of the two slides are offset with respect to each other so as 55

to overlap with a space between sufficient to receive an idler gear or pinion 24 in mesh with both racks. This construction necessitates that both slides must move substantially simultaneously in opposite directions and change their direction of movement substantially simultaneously. The pinion is shown as mounted upon the lower end of coupling A as a pivot. Furthermore, the pinion, as well as the racks and inner ends 10 of the slides are shown held upwardly in place toward the housing by U-shaped brackets 25 extending longitudinally of the housing and slides and fixed to the housing as by bolts 26.

The slides 15 as here shown, provide integrally formed flanges 27 extending laterally from opposite sides thereof next the bottom of the slides so as to constitute what may here be termed a platen. The working tool to be operated by the machine is attached against the underside of the platen. The two tools will be operated simultaneously toward each other and simultaneously away from each other thereby reducing vibration of the body of the machine to a minimum.

It is a feature of the present invention to provide proper lubricating means for all of the working parts and enable the lubricant to be injected only at one place by the operator. As here shown, a one-way lubricating fitting 28 is shown at one side of the housing. Details of this fitting are well known in the art, they being constructed to admit lubricant from the exterior, but having a one-way ball valve means therein for preventing return of the lubricant or other pressure from escaping. Such a fitting is here employed and shown particularly in Figure 5 as entering the air conveying passages at the juncture of the main channel 17 with coupling A where the passage through the coupling opens into said channel. It may accordingly be here noted that the coupling A, in the part extending from channel 17 downwardly to its end forming the pivot for pinion 24 has a lubricant duct 29 therein substantially to its lower end where a transverse oil hole 30 radially of the fitting will permit grease or other lubricant to pass from the duct to the surface between the fitting and pinion. The lubricant introduced into the main channel 17 will be carried by the operating air or other fluid into the cylinders 11 for lubricating the pistons, and some will be carried out of the exhaust port 22. Preferably the exhaust port 22, at the exhaust period, registers with a transverse slot 31 in the upper face of the slide 15. This slot 31 is transverse to the several serrations in the upper face 55 of the slide, and preferably the peaks of the ridges of the serrations in both the housing and slide are rounded off or otherwise shaped so as to provide space between the ridges of the serrations and the juxtaposed valleys thereof. The exhaust fluid pressure will therefore spread laterally in slot 31 and then escape through the several spaces longitudinally of the serrations. Lubricant is carried with this exhaust air and accordingly maintains the desired lubricated condition between the slide and the housing.

According to the present invention, I may provide a buffing tool 32 to be secured to the aforesaid platen or underside of the flanges 27. This tool is shown as providing a plate 33 on the underside of which is held buffing material such as a felt pad 34. The pad is preferably secured to the plate by means of depressed nuts 35 in the pad, receiving screws 36 projecting into the pad from said plate 33. The tool is secured flatwise

against flanges 27 of the platen by suitable bolts 37.

Another tool 38 more especially intended for mounting sheet abrasive, such as sand-paper is shown in Figure 7 attached to the flanges 27 of the platen by said bolts 37. This tool preferably provides a lower plate 39 as a bearing surface for the sheet of abrasive 40. Upstanding side flanges 41 space this plate 39 from the flanges 27 of the platen and provide means for receiving the attaching bolts 37. Between said lower plate and the platen and at the opposite ends of the tool which in use are transverse to the direction of movement of the tool are jaws 42. These jaws may conveniently provide one member 43 pivoted at 44 to the upstanding flange 41. The other jaw member 45 is pivoted as at 46 to the first said jaw member and has associated in fixed relation to the said other jaw member 45 an upwardly projecting crank arm 47. From the upper end of this crank arm 47 extends a rod 48 projecting toward the middle of the tool and having a nut 49 at its inner end. Near the pivoted end of this rod 48 the same passes through a yoke 51 or similar part of an eccentric bar 52 extending substantially parallel to the rod 48. A compression spring 53 is upon the rod and bears at its ends against nut 49 and yoke 51. An eccentric 54 operated by a screw-head 55 at the outside of flange 41 will move eccentric bar 52 longitudinally thereby either tensioning the spring or releasing the tension thereof depending upon the turning of the eccentric and screw-head. When the spring is placed under pressure, it tends to close the jaw members together to grip the abrasive sheet and likewise tends to swing the jaws upwardly as a unit, thereby placing tension on the sheet. This tension is in the longitudinal direction of the sheet corresponding to the direction of movement to which the sheet is subjected in the operation of the machine. It will be seen that replacement of the abrasive sheet and tensioning of the same is accomplished with the greatest of ease and is under the simple control of the screw-head 55.

It will furthermore be understood that by virtue of the guiding serrations between the body of the machine and the slides, that there will be no lateral deviation of the direction of movement of the particular tool employed. This lends itself to enabling the tool to be used for producing a very smooth and high polish. Furthermore, the straight-line reciprocation of the tools with both tools acting in alinement, enables the same to be used upon surfaces which are longitudinally regular but transversely irregular, such as mouldings. The face of the tool toward the work when of such irregular character, may be shaped, as will be understood, to agree with the shape of the surface being acted upon.

I claim:

1. A machine as characterized comprising a housing providing a single boring the ends of which constitute opposed cylinders, each of said cylinders having a piston and a piston rod, a coupling mounted at the outer end of each of said piston rods, a pair of slides underneath said housing, each slide being beneath its respective piston and made fast with respect to the piston rod thereof by said coupling for obtaining in said slides a double reciprocating motion, and said slides each having means for attaching a tool thereto.

2. A machine as characterized comprising a housing providing a single boring the ends of

- which constitute opposed cylinders, each of said cylinders having a piston and a piston rod, each of said piston rods at their outer ends having a connecting means mounted thereon, a pair of slides 5 underneath said housing, each slide being beneath its respective piston and made fast with respect to the said piston rods by said connecting means for obtaining in said slides a double reciprocating motion, and inter-engaging means between said 10 slides adapted to synchronize operation of the said slides in opposed directions, and means on the underside of said slides for each mounting a tool thereon.
3. A machine as characterized comprising a 15 housing providing a single boring the ends of which constitute opposed cylinders, each of said cylinders having a piston and a piston rod, each of said piston rods at their outer ends having a connecting means mounted thereon, a pair of 20 slides underneath said housing, each slide being beneath its respective piston and made fast with respect to the said piston rods by said connecting means for obtaining in said slides a double reciprocating motion, and a pinion meshing with respect to both slides adapted to synchronize operation 25 of the slides in opposed directions, and means on the underside of said slides for each mounting a tool thereon.
4. A machine as characterized comprising a 30 housing providing a single boring the ends of which constitute opposed cylinders, each of said cylinders having a piston and a piston rod, each of said piston rods at their outer ends having a connecting means mounted thereon, a pair of 35 slides underneath said housing, each slide being beneath its respective piston and made fast with respect to the said piston rods by said connecting means for obtaining in said slides a double reciprocating motion, a pair of overlapping racks 40 one on each of said slides, and a pinion between and meshing with said racks adapted to synchronize operation of the slides in opposed directions, and means on the underside of said slides for each mounting a tool thereon.
- 45 5. A machine as characterized comprising a housing providing a single boring the ends of which constitute opposed cylinders, each of said cylinders having a piston and a piston rod, each of said piston rods at their outer ends having a connecting means mounted thereon, a pair of 50 slides underneath said housing, each slide being beneath its respective piston and made fast with respect to the said piston rods by said connecting means for obtaining in said slides a double reciprocating motion, and a pinion meshing with respect to both slides adapted to synchronize operation 55 of the slides in opposed directions, and means on the underside of said slides for each mounting a tool thereon, and brackets for supporting the inner ends of the slides maintaining the same in alinement and in sliding contact with the housing.
- 60 6. A machine as characterized comprising a housing providing a single boring the ends of which constitute opposed cylinders, each of said cylinders having a piston and a piston rod, each 65
- of said piston rods at their outer ends having a connecting means mounted thereon, a pair of slides underneath said housing, each slide being beneath its respective piston and made fast with respect to the said piston rods by said connecting means for obtaining in said slides a double reciprocating motion, a pair of overlapping racks one on each of said slides, and a pinion between and meshing with said racks adapted to synchronize operation of the slides in opposed directions, and means on the underside of said slides for each mounting a tool thereon, and brackets for supporting the pinion and the inner ends of the slides maintaining the same in alinement and in sliding contact with the housing. 10
7. A machine as characterized comprising a housing having a fluid actuated piston, and a slide next the housing for imparting reciprocation to a tool and the like from reciprocation of the piston, said slide and housing providing longitudinal inter-engaging serrations for guiding and receiving pressure of the slide with respect to the housing, said housing providing means for discharging the exhaust from the actuation of the piston between the serrations of the slide and 15 housing. 20
8. A machine as characterized comprising a housing having a fluid actuated piston, and a slide next the housing for imparting reciprocation to a tool and the like from reciprocation of the piston, said slide and housing having bearing surfaces and intervening non-bearing surfaces, said housing providing means for discharging the exhaust from the actuation of the piston between the non-bearing surfaces of the slide and housing, and means for introducing lubricant into the actuating fluid for the piston and thereby lubricate both the piston and the bearing surface of sliding contact between the slide and housing. 30
9. A machine as characterized comprising a housing having a fluid actuated piston, and a slide next the housing for imparting reciprocation to a tool and the like from reciprocation of the piston, said slide and housing providing longitudinal interengaging serrations for guiding and receiving pressure of the slide with respect to the housing, and means for introducing lubricant into the actuating fluid for the piston and passing it through said serrations thereby lubricating both the piston and the surface of sliding contact between the slide and housing. 35
10. A machine as characterized comprising a housing having a fluid actuated piston, and a slide next the housing for imparting reciprocation to a tool and the like from reciprocation of the piston, said slide and housing providing longitudinal inter-engaging serrations for guiding and receiving pressure of the slide with respect to the housing, said housing providing means for discharging the exhaust from the actuation of the piston between the slide and housing through said serrations, and means for introducing lubricant into the actuating fluid for the piston and thereby lubricate both the piston and the surface of sliding contact between the slide and housing. 40

WILLIAM O. ARNOLD.
